United States Patent

Des. 236,979
Patented Sept. 30, 1975

236,979

EDUCATIONAL MEASURING DEVICE BOARD

Charles G. Valentine, Stamford, Conn., assignor to
Xerox Corporation, Stamford, Conn.

Filed Apr. 27, 1973, Ser. No. 355,223

Term of patent 14 years

Int. Cl. D19—07

U.S. Cl. D19—62

FIG. 1

FIG. 2

FIG. 1 is a right perspective view of an educational measuring device board showing my new design; and

FIG. 2 is a left perspective view thereof.

The rear of the educational measuring device board not shown is plain and unornamented.

I claim:

The ornamental design of an educational measuring device board, substantially as shown and described.
